CYLINDER RIDGE REAMER

Wallace F. Mitchell, Chicago, Ill., assignor to
 Automotive Maintenance Machinery Co., North
 Chicago, Ill., a corporation of Illinois

Application October 2, 1942, Serial No. 460,517

7 Claims. (Cl. 77—58)

My invention relates generally to tools for truing up worn cylinders and it has to do particularly with a so-called ridge reamer adapted for the removal of circumferential ridges formed by wear occasioned by movement of piston rings along a cylinder wall surface.

It is well known that piston rings tend to wear away the cylinder wall surface throughout their range of travel, the upper limit of such travel being below the top of the cylinder so that the wear occasioned by the rings leaves a ridge surface around the top of the cylinder. This ridge will be referred to at times as a "ring-wear" ridge. In the reconditioning of cylinders it is desirable that this ridge be removed; otherwise, when a new and unworn square-edge ring is installed the upper edge of the ring may strike the ridge and produce a sharp clicking sound. While this action is not at first objectionable from proper ring-seal standpoints it causes increased and rapid wear of the rings with the result that they break down and cease to function properly in a comparatively short time.

It is also well known that cylinders, at the points of wear, tend to wear to a greater extent on one side of the center line than on the other and may wear in an oblong shape. For this and other reasons well known to those skilled in the art, the above-mentioned ridge may be of irregular shape and depth which presents a problem in removing the same.

One of the objects of my invention is to provide an improved tool of the foregoing character which is of simple and sturdy construction and which is adapted for removal in a rapid and highly efficient manner of ridges formed in cylinders by ring wear.

Another object is to provide a ridge reamer having a cutting blade which is automatically fed in cutting direction.

Still another object is to provide a ridge reamer of the foregoing character having provision for limiting the extent of the cutting action.

Other objects are to provide adjustable stop means operable under the control of the cylinder wall surface for determining the extent of cut of the reamer and to insure complete removal of a ring-wear ridge regardless of variation in depth of the same; and to provide an automatically fed reamer blade having an adjustable stop thereon which is aligned with its ridge cutting edge and adapted to engage the cylinder wall to cause the blade to remove the ring-wear ridge flush with the adjacent cylinder wall surface.

Other objects and advantages will become ap-

parent as this description progresses and by reference to the drawings wherein,

Figure 1 is an elevational view of one form of tool embodying my invention, the same being shown applied to a cylinder having a ring-wear ridge of uniform depth to be removed;

Fig. 2 is a section taken substantially on line 2—2 of Fig. 1;

Fig. 3 is a section taken substantially on line 3—3 of Fig. 2;

10 Fig. 4 is a section taken substantially on line 4—4 of Fig. 1;

Fig. 5 is a section taken substantially on line 5—5 of Fig. 1;

15 Fig. 6 is a longitudinal sectional view taken substantially on line 6—6 of Fig. 4;

Fig. 7 is an enlarged fragmental view showing the reamer blade of the tool of the previous figures in position for removal of a ring-wear ridge;

Fig. 8 is a view similar to Fig. 7 and showing 20 the reamer blade in position after removal of the ridge of Fig. 7; and

Fig. 9 is an enlarged fragmental view showing in full and dotted lines the tool of the previous figures in position in a cylinder ready for removal 25 of a ring-wear ridge of varying depth.

In the drawings, I have shown my invention applied to a tool adapted particularly for the removal of a ring-wear ridge 10 (Figs. 1, 6, 7 and 8) formed in the cylinder 11 of an internal combustion engine; however, it is to be understood that my invention has utility in any instance where similar problems and conditions of use are involved. For the purpose of explanation the 30 ridge 10 is shown in Fig. 1 as of uniform depth and in Fig. 9 as of varying depth.

The tool illustrated embodies a supporting section A which is adapted to be mounted in the cylinder 11 below the ridge 10 so as to rigidly support the tool as a whole therein. It also includes a reamer section B which is rotatably carried by the supporting section A, the reamer section including a cutting blade 12 which is adapted to engage the ring-wear ridge 10 and remove the 35 same as the reamer section B is rotated.

The support section A includes a top plate 13 (Figs. 1 and 6) having a tubular cylindrical extension 14 on its upper side. A plurality (preferably three) of depending posts 15 are rigidly secured at their upper ends, as at 16, to the top plate 13, which posts pass through openings in a movable bottom plate 17 to guidingly center and support the same. The posts 15 define radial passageways (Fig. 5) in which are disposed blade-like support members 18 (Figs. 1, 5 and 6), the

upper edges 18^a of which are snugly and slidably received in radially directed grooves 13^a in the lower side of the top plate 13. The bottom plate 17 is provided with a plurality of radially directed grooves 17^a which are aligned with the top plate 13^a in which the lower and inclined edges 18^b of the support members 18 are received. The bases of the grooves 17^a are tapered upwardly and inwardly for engagement with the complementally shaped edge portions 18^b of the support members 18.

The support members 18 (Fig. 6) are expandable and contractible to engage the support section A with and release it from the wall of the cylinder 11 and, to this end, the bottom plate 17 is shifted axially of the tool. Upward movement of the bottom plate 17, because of the complementally tapered surface of the bottom plate groove 17^a, expands the support members 18 and this expansion movement is yieldingly opposed by a garter spring 19 (Fig. 5) which tends at all times to urge the support members 18 in a contracting direction so that when the bottom plate 17 is moved downwardly the support members are contracted to release the tool from the cylinder. Movement of the bottom plate 17 in opposite directions is accomplished by an adjusting stem 20, the lower end 20^a of which is threaded to engage a threaded opening 17^b in the bottom plate 17. The stem 20 extends upwardly and rotatably through an axial opening 14^a in the end plate extension 14 and outwardly therebeyond to receive an adjusting nut 21 which will be described further hereinafter.

The end plate extension 14 (Fig. 6) rotatably supports the reamer section B. This reamer section comprises a body 22 having an axial bore 22^a in its lower end in which the end plate extension 14 is rotatably received. Tensioned rotational movement of the reamer section B upon the extension 14 is provided by a spring-pressed ball 23 carried by the body 22 and engaging a circumferential groove 24 in the end plate extension 14. The body 22 is further provided with a reduced axial bore 22^b connecting with the bore 22^a and through which the outer end portion of the adjusting stem 20 passes, the body being further provided with an enlarged cage-like head 22^c having an enlarged transverse slot or opening 25 in which the adjusting nut 21 is rotatably confined against longitudinal displacement. This adjusting nut 21 is secured to the upper or outer end of the adjusting stem 20 by a pin 26 (Fig. 6). The adjusting stem 20 is confined rotatably between the body 22 and the end plate extension 14 by a collar 27 pinned thereto as at 27^a and located in the bore 22^b at the outer end of the end plate extension 14. With this arrangement the adjusting nut 21 may be rotated in opposite directions to rotate the stem 20 without longitudinal displacement thereof to move the bottom plate 17 up or down to expand or contract the support members 18. The reamer section A is rotated independently of the adjusting stem 20 and nut 21 to effect the reaming operation. The reamer section B is preferably rotated by hand but, if desired, any suitable power means may be employed. As shown in the drawings, the upper end or head 22^c of the reamer body is provided with an outwardly extending rectangular shank 28 to which any suitable tool, such as a wrench, may be applied for rotating such body.

Only one cutting blade 12 is employed (Figs. 1-4), the same being supported by the rotatable

body 22 in such a way that the blade cuts with a so-called drag-cut or scraping action thereby eliminating chatter and any dig-in tendencies and providing a smooth and clean cut. The blade 12 is so mounted and actuated that, during the reaming operation, it is automatically fed toward the ridge to be reamed so that repeated adjustment of the blade is not required in order to completely cut away such ridge. It is desirable that the ridge be neither undercut nor overcut, and to insure the cutting away of the ridge to the proper extent, namely, flush with the cylinder wall surface therebeneath, my invention provides means cooperative with the cylinder wall beneath the ridge 10 (or 45^a-45^b, Fig. 9) to limit the extent of feed of the cutting blade and, in turn, the depth of the cut. This arrangement is such that even though the depth of the ridge to be cut may be varied, the cutting action will be such that the ridge will be cut down flush with the cylinder wall throughout the circumference of the cylinder.

To the foregoing end, the cutting blade 12 is supported in a transverse slideway 29 (Figs. 2-6) formed in the body 22 to one side of and tangentially of the axis thereof. To permit assembly and removal of the cutting blade the outer part of the slideway comprises a removable plate 30, the lower end of which is confined in a groove 31 (Fig. 2) and the upper end of which is secured in place by a screw 32.

Adjustment and feed of the cutting blade 12 is provided for in the manner which will now be described. The inner face of the blade 12 is provided with a diagonal groove 33 extending upwardly and rearwardly from the forward end thereof. Expansion and contraction movements of the blade are accomplished by an actuator unit which comprises a vertical slide member or actuator 34 of general semicircular shape mounted in a similarly shaped slideway 35 (Figs. 2 and 6) located inwardly of and extending downwardly along and above the blade 12. The lower end of slide member 34 is provided with a cam or lug 36 shaped complementally to and fitting snugly in the blade slideway 33. It will thus be seen that by moving the slide member 34 upwardly so that the slide cam 36 approaches the rear or upper end of the blade groove 33, the blade 12 is displaced outwardly; and when the slide member 34 is moved downwardly so that the cam 36 approaches the forward end of the slide 33, the blade 12 is retracted.

Movement of the slide member 34 and blade 12 in initially setting the tool in a cylinder for the reaming operation may be accomplished manually, the actual movement of the slide member 34 and feed of the blade during the reaming operation being accomplished automatically. Specifically the upper end of the slide member 34 is provided with a threaded extension 37 which projects upwardly and outwardly beyond the slideway 35 where it receives an adjusting abutment or nut 38. The upper end of the slideway 35 is covered by a washer-like closure 39 having an opening through which the threaded stem 37 freely passes. A spring 40 is confined between the outer end of the washer 39 and the adjusting nut 38. The reamer body 22 is provided with a recess or well 41 immediately beneath the cage-like head 22^c. The slide member stem 37 projects into the well 41 so that the nut 38 is disposed therein with the underside of the body head 22^c serving as a stop abutment limiting the upward or outward movement of the nut 38. The

spring 40 is so constructed that it is under slight tension when the nut 38 abuts the head 22^c.

With the foregoing arrangement, assuming that the tool is in position in a cylinder, as shown in Fig. 1, and it is desired to retract the cutting blade, the adjusting nut 38 is rotated in a counterclockwise direction until its upper end abuts the head 22^c of the body 22. Further rotation of the nut 38 will then move the slide member 34 and its feather 36 downwardly to retract the blade, as above explained. Conversely, when it is desired to expand the blade from its contracted condition, the nut 38 is rotated in a clockwise direction, thereby drawing the slide 34 and its feather 36 upwardly to move the blade 12 outwardly.

In use, assuming that a ridge 10, such as shown in Fig. 1, is to be removed, the tool is first applied to the cylinder with the support members 18 disposed below the ridge 10. The adjusting nut 24 is then rotated in a clockwise direction to move the bottom plate 17 upwardly and expand the support members 18 into firm engagement with the cylinder wall. After this the nut 38 is first manually rotated in a clockwise direction to expand the blade 12 to engage its cutting edge 12^a with the ridge 10. After the blade is engaged with the ridge 10 the nut 38, preferably, is further rotated sufficiently to completely compress the spring 40 and is then backed off, so to speak, one or two turns. In this way the nut 38 is moved away from the body head 22^c permitting upward movement thereof to expand the blade and the spring 40 is placed under compression and conditioned to yieldably urge the slide 34 and its feather 36 upwardly to move the cutting blade 12 outwardly in expanding direction. With the blade 12 so set a wrench or other tool is applied to the shank 28 to rotate the reamer section B and, as this takes place, the blade 12 cuts away the ridge 10, the blade automatically expanding as the metal is cut away to completely remove the ridge 10.

As above pointed out, it is highly desirable that the ridge 10 be cut away to an extent flush with the cylinder wall surface therebeneath. It will be appreciated that it would be extremely difficult, and impractical, for an operator to attempt to determine, while rotating the tool, just when that flush condition is reached so that, unless otherwise provided against, the ridge may be cut away too much or too little with resultant deleterious effects well recognized by those skilled in the art. To guard against this my invention provides stop means which prevents further reaming when the ridge is cut away flush with the cylinder wall therebeneath.

More particularly, the cutting edge 12^a terminates short of the lower edge of the blade 12 providing a notch forming a land or ledge 42 (Figs. 1, 3, 7-9) at the lower forward edge of the blade 12 adjacent the wall of the cylinder 11. On the ledge 42 I provide a stop member 43 which takes the form of a screw engaging in a suitably threaded opening in the ledge 42. The outer end of the screw 43 is provided with a rounded or hemispherical button-like end 43^a inwardly of which is a hexagonal or other suitably shaped portion 43^b which may be engaged to screw the same into the ledge opening. The screw is secured in adjusted position by a lock nut 44.

In use, the stop member 43 is adjusted to a position wherein the outer surface of its button-like end 43^a is in vertical alignment with that portion of the blade cutting edge 12^a which will

engage the lower or bottom edge of the ridge 10. It will be noted that the cutting edge 12^a of the blade 12 is slightly tapered downwardly and inwardly (preferably a 2° taper) so as to cut away the ridged portion of the cylinder on a slight bevel. I have found in practice that excellent results may be obtained by positioning the tool in the cylinder to such a depth that the button-like end of the stop member 43 is approximately one-quarter of an inch below the lower edge of the ridge 10. It will be seen that with this arrangement, as soon as the lower edge of the ridge 10 is cut away (Fig. 8) to an extent wherein it is flush with the cylinder wall, the stop member 43 engages the cylinder wall thereby preventing further expansion movement of the cutting blade 12 and, in turn, further reaming of the cylinder surface. The head or end 43^a of the screw, being rounded and of relatively small size, has a substantially point contact with the cylinder wall and presents no surface on which chips from the cutting operation can lodge. Moreover, the screw head is located slightly to the rear of the cutting edge as is evident in Fig. 4 so that the chips, which are thrown forwardly by the cutting action, fall clear of the screw. Thus, the chance of the cylinder wall being scored by such chips wedging between the screw head and the wall as well as scoring by the tool due to such wedging is avoided. It will be noted that, since the screw 43 is at the outer end of the blade, the screw may be adjusted without necessitating removal of the blade from the body member.

The foregoing arrangement, including the automatically-fed cutting blade and the stop means limiting the feed of the blade, enables one to cut away a ridge caused by ring wear uniformly throughout its circumference, notwithstanding the fact that such ridge may be of varying depth, as hereinabove explained. Such a ridge is shown at 45^a and 45^b in Fig. 9, the ridge portion 45^b being of greater depth than the ridge portion 45^a. In view of the fact that the automatic feed of the cutting blade will take place and the reaming operation will continue until the stop member 43 engages the cylinder wall throughout its circumference, the reaming operation, while stopped at 45^a (Fig. 9), will continue at 45^b (Fig. 9) and at points therebetween. As soon as the stop member 43 contacts the cylinder throughout its circumference, which action can readily be felt by the operator, the reaming operation is complete, no further material will be removed, and the tool may be removed from the cylinder. When so removed, outward movement of the blade is limited by contact of the nut 38 and the head 22^c.

I believe that the operation and advantages of my invention will be obvious from the foregoing description. My invention not only provides a very simple and sturdy tool for the purpose stated, but it also provides a tool wherein the ridge reaming operation may be carried on more quickly than heretofore and with greater accuracy. My invention also insures more efficient reconditioning of worn cylinders at less expense. It also provides a tool which may be used with the desired accuracy by unskilled labor without danger of over-reaming or under-reaming the ridge. It also provides an arrangement wherein different portions of the cutting edge 12^a may be employed with the desired accuracy. For example, if the lower part of the cutting blade is used for a time, as illustrated in Fig. 1, and becomes dull, the tool may be lowered in the cylinder and the upper or

sharp part of the edge may be used. In that case, and to accommodate the different depths of the tool in the cylinder, due to the taper of the cutting edge 12^a, the stop member 43 may be adjusted so as to properly align with that portion of the cutting blade which will engage and cut the bottom edge of the ridge, thereby preventing the blade from cutting to an extent deeper than the cylinder wall surface below the ridge.

I claim:

1. In a tool adapted for removal of ring-wear, or the like, ridges formed on the wall of a cylinder, a body member, means for supporting said body member for rotational movement, a cutting blade slidably carried by said body member for substantially radial outward expanding and inward contracting movement and having a cutting edge on the outer end thereof, means for automatically feeding said blade outward to cut away the ridge, said blade having a notch cut in its lower outer corner, a round-headed screw located in said notch and threaded generally radially into said blade with its head outward to contact the cylinder wall beneath the ridge to limit the expanding movement of said feeding means, and a lock nut on said screw to lock the screw with its head in alignment with the cutting edge of said blade to limit the cutting action to removal of the ridge.

2. In a tool adapted for removal of ring-wear, or the like, ridges formed on the wall of a cylinder, a body member, means for supporting said body member for rotational movement, a cutting blade slidably carried by said body member for substantially radial outward expanding and inward contracting movement and having a cutting edge on the outer end thereof, means for automatically feeding said blade outward to cut away the ridge, and a screw threaded generally radially into said blade with its head outward to contact the cylinder wall beneath the ridge to limit expanding movement of said feeding means, the head of said screw being generally hemispherical to provide substantially point contact with the cylinder wall and to provide a rounded upwardly facing surface of relatively small dimension to prevent chips from collecting on said head and wedging between said screw and the cylinder wall.

3. In a tool adapted for removal of ring-wear, or the like, ridges formed on the wall of a cylinder, a body member, means for supporting said body member for rotational movement, a cutting blade slidably carried by said body member for substantially radial outward expanding and inward contracting movement and having a cutting edge on the outer end thereof, means for automatically feeding said blade outward to cut away the ridge, and a round-headed screw threaded generally radially into said blade with its head outward to contact the cylinder wall beneath the ridge to limit expanding movement of said feeding means, said screw being positioned with its head rearwardly of the cutting edge of said blade whereby the chips will fall clear of said screw.

4. In a tool adapted for removal of ring-wear, or the like, ridges formed on the wall of a cylinder, a body member, means for supporting said body member for rotational movement, a cutting blade slidably carried by said body member for

substantially radial outward expanding and inward contracting movement and having a cutting edge on the outer end thereof, means for automatically feeding said blade outward to cut away the ridge, and a stop member mounted on the outer end of said blade to contact the cylinder wall beneath the ridge to limit expanding movement of said feeding means, said stop member being adjustable relative to said blade and accessible for such adjustment at the outer edge of said blade whereby such adjustment may be made when the blade is assembled in operative relation with said body member.

5. In a tool adapted for removal of ring-wear, or the like, ridges formed on the wall of a cylinder, a body member adapted to be supported for rotational movement, a cutting blade slidably carried by said body member for radially outward expanding and inward contracting movement, and spring-loaded means carried by said body member for automatically feeding said blade in an expanding direction, said means extending upwardly above the cylinder and having means for adjusting the spring pressure located above the cylinder for convenient adjustment when the tool is positioned within the cylinder.

6. In a tool adapted for removal of ring-wear, or the like, ridges formed on the wall of a cylinder, a body member adapted to be supported for rotational movement, a cutting blade slidably carried by said body member for radially outwardly expanding and inward contracting movement, an actuator for said blade mounted in said body member and having a threaded end portion, said body member having a recess into which said threaded end portion extends, a spring surrounding said threaded portion and held by said body member against movement at one end, and a nut on said threaded portion and bearing against the other end of said spring to place the latter under compression, said nut being adjusted on said threaded portion so that, when the blade is in engagement with the cylinder wall, the nut is held in spaced relation to the adjacent side of said recess, the nut being adapted to engage said side when the blade is removed from the cylinder to prevent excessive outward movement of said blade.

7. In a tool adapted for removal of ring-wear, or the like, ridges formed on the wall of a cylinder, a body member adapted to be rotated and having a portion adapted to extend into the cylinder for securement thereto and a portion extending above the cylinder with a recess in said extending portion, a cutting blade slidably carried by said body member for radially outward expanding movement and inward contracting movement, an actuator engaging said blade and movable to expand and contract the blade, a spring mounted on said actuator and bearing at one end against one side of said recess, and an abutment adjustably mounted on said actuator and bearing against the other end of said spring, said abutment being adjustable in one direction to place said spring under pressure for expanding said blade with said abutment spaced from the other side of said recess and being adjustable in the other direction to bear against said other side of said recess to contract said blade.
